CLAIM

The ornamental design for a magnetic battery storage device as shown and described.

DESCRIPTION

FIG. 1 is a front perspective view of a magnetic battery storage device showing my new design.

FIG. 2 is a front view thereof.

FIG. 3 is a first side view thereof.

FIG. 4 is a second side view thereof.

FIG. 5 is a rear view thereof.

FIG. 6 is a top view thereof.

FIG. 7 is a bottom view thereof; and,

FIG. 8 is another front perspective view of a magnetic battery storage device, with a battery shown attached thereto.

The broken lines in the drawings represent environmental subject matter and form no part of the claimed design.

1 Claim, 6 Drawing Sheets
